UNITED STATES PATENT OFFICE.

ANSLEY BARNES, OF WATERVILLE, MAINE.

CABLE-TIGHTENER.

1,389,475.

Specification of Letters Patent. Patented Aug. 30, 1921.

Application filed June 14, 1920. Serial No. 288,879.

To all whom it may concern:

Be it known that I, ANSLEY BARNES, a citizen of the United States, residing at Waterville, in the county of Kennebec and State 5 of Maine, have invented certain new and useful Improvements in Cable-Tighteners; and I do declare the following to be a full, clear, and exact description of the invention, such as will enable others skilled in the art to 10 which it appertains to make and use the same.

This invention relates to cable tighteners broadly, and more specifically to a device of this class which is especially designed for 15 stretching guy wires of telegraph and telephone poles, fence wires, and the like.

One object of the invention is to generally improve upon, simplify, strengthen, and reduce the cost of manufacture of my Patent 20 No. 1,143,483 granted to me on June 15, 1915.

Another and important object of the invention is to improve upon my patented device by making the rack bar solid and omitting the guide slot, and to equip the bar at 25 one end with a shoulder against which the fulcrum block of the wire link carrying arm abuts, permitting said arm to be swung to such an angular position that, when its free end is moved downwardly toward said bar, 30 the initial slack in the wire will be taken up.

A further object of the invention is to so construct the present device that the parts may be more readily disconnected and placed in a compact package for shipping and 35 packing.

Other objects and advantages of the invention will be apparent during the course of the following description.

In the accompanying drawings forming 40 a part of this specification and in which like numerals are employed to designate like parts throughout the same:

Figure 1 is an elevational view of a tool constructed in accordance with my invention.

Fig. 2 is an enlarged elevational view, with parts in section showing the pivoted toothed arm in the angular position it assumes in order to take up the initial slack.

Fig. 3 is a top plan view thereof.

In the drawings, wherein for the purpose of illustration is shown a preferred embodiment of my invention, the numeral 1 designates a rack bar which is provided at one 55 end with means for permitting attachment of the wire to be stretched. This means

may be of any suitable construction, being here shown in the form of a swiveled hook 2.

Pivotedly and slidably mounted on the bar 1 is a second bar or arm 3 which carries a link or clevis 4, by means of which the tool is anchored upon a stationary support. The bar 3 may be connected to the bar 1 in any suitable way. However, by preference, I equip it with a pair of ears 5 which straddle 65 the bar 1 and permit the aforesaid to sliding and pivotal movement. To complete this connection I dispose a fulcrum block 6 between the free ends of the ears and this block slides on the lower edge of the bar 1. 70 To lock the bar 3 in the various positions to which it has been moved, I make use of a dog 7 which is preferably carried thereby and is engageable with the teeth 8 of the bar 1, the dog being retained in either effective or ineffective position by a suitable spring 9. In order to facilitate disengagement of the dog from the teeth 8, I provide it with a shoulder 10, behind which the finger may be placed for the purpose of 80 lifting the dog.

A bifurcated hand operated lever 11 is pivoted on the bar 1. This lever is adapted to impart sliding movement to the bar 3. To accomplish this I extend a pin 12 transversely 85 through the furcations of the lever, this pin being designed to seat between the teeth 13 along the adjacent edge of the bar 3. Up to this point, the construction described is substantially the same as that disclosed in 90 my patent with the exception of the swiveled hook 2 and fulcrum block 6 which are two of the new features of the present device.

One of the main differences between the present device and my patented device resides in the fact that in the present device, I provide the bar 1 adjacent one end and on its opposite sides with a pair of shoulders 95 14 and 15, the first named of which is designed to be engaged by the adjacent end 100 of the bar 3, while the latter is designed to coact with the fulcrum block 6. This particular construction and arrangement of parts permits the bar 3 to be moved to and held in the angular position shown in Fig. 105 2.

With the parts in this position and assuming that the wire has been connected to the hook 2 and the link 4 anchored on a post or the like, it will be seen that by forcing the free end of this bar downwardly, the 110 initial slack in the wire will be partially taken up prior to any sliding movement of

the bar, which brings about the final tightening of the wire. It is also the purpose of this construction to prevent the bar 3 from becoming accidentally disconnected from the bar 1. Furthermore, I prefer to use this construction because it is less expensive, more simple, and enables me to easily and readily disconnect the parts for placing the device in a compact package for shipment. 10 It will be recalled that in my patented device the bar 1 instead of being constructed in the manner herein shown and described is equipped with a slot in which a stop pin slides, the latter being a part of the link carrying bar. I have found upon constant use of the device constructed in that manner, that it is not entirely effective and desirable. For this reason I prefer the construction disclosed in the present application because of 20 the fact that it possesses features already set forth which my patented device does not possess.

In operation, the cable, wire or other element to be stretched is connected directly or 25 by means of grip devices of well known construction with the hook 2 which, as before stated, is swiveled to permit free rotation of the cable which ordinarily turns when under tension and is liable to break the 30 hook if it was stationary. Next, the link or clevis 4 is secured to a suitable stationary support in any desired manner. Assuming that the bar 3 and lever 11 are in the position disclosed in Fig. 2, it will be seen that 35 the initial slack may be taken up in the way already described. Now, after the parts are placed in the position shown in Fig. 1 and by rocking the lever, the member 3 will be moved along the bar 1 and in so doing 40 will place the cable under tension. As the cable is so stretched, the dog 7 is automatically engaged with the teeth 8 of the bar 1, thus, the bar 3 is retained in the position to which it has been moved by the action of 45 the operating lever, as is obvious. After the cable has been tightened sufficiently, it may be secured in position in the usual way.

I desire to call attention to the fact that the construction employed in this device is 50 far more simple and a great deal more advantageous than that disclosed in my patented device. For instance, if it is desired to disconnect the parts of the device, all that is necessary to do is to remove the bolt which connects the operating lever with the bar 1. Then, this bar may be slid from right to left between the ears 5, and readily removed. It may be just as easily replaced. This feature is not true with the construction employed in my patented device. Due to this 60 easy and simple method of disconnecting the parts, it will be seen that the device may be conveniently packed. The swiveled hook employed in this device is advantageous, and 65 the dog with the finger grip, is also advan-

tageous. These, and other points of difference already apparent from the foregoing description render the present device more desirable and advantageous than my patented device or any other similar patented 70 device with which I am familiar.

A careful consideration of the foregoing description taken in conjunction with the accompanying drawings will enable persons skilled in the art to which this invention 75 appertains, to obtain a clear understanding of the same, therefore, further description is deemed unnecessary.

It is to be understood that the form of my invention herein shown and described 80 is to be taken as a preferred form of the same, and that various minor changes in the shape, size, and arrangement of parts may be resorted to without departing from the spirit of the invention or the scope of the 85 subjoined claims.

I claim:

1. A tool of the class described comprising a rack bar provided with means for connection to the wire to be stretched, being 90 also provided at one end with a shoulder, an arm pivotally and slidably mounted on the bar and engageable at its pivoted end with said shoulder to permit initial slack in the wire to be partially taken up when the 95 arm is swung downwardly on its pivot, means for sliding said arm on the bar, and a pawl carried by the arm and engageable with the teeth on said rack bar.

2. A tool of the class described comprising a rack bar having one of its ends laterally offset, made at this end with a pair of lateral projections forming shoulders, an arm pivotally and slidably mounted on said bar and having its pivoted end engageable 105 with one of the shoulders, said arm being provided at its pivoted end with a bifurcated head, the furcations forming ears straddling said bar and extending below the lower edge thereof, a fulcrum block pivoted 110 between said ears and slidably engaging the adjacent lower edge of the bar, said block being engageable with the remaining shoulder to limit the movement of the arm in one direction, a spring-pressed dog also pivoted 115 between said ears and extending beyond the adjacent end of said arm and being engageable with the teeth on said rack bar, and means for imparting a sliding movement to said arm.

3. A tool of the class described comprising a rack bar laterally offset at one end and provided at this end with a pair of shoulders, a wire attaching hook swiveled on the opposite end of the bar, an arm provided 125 along its lower edge with teeth, and equipped at one end with a head including spaced ears straddling said bar and extending below the lower edge thereof, a portion of said arm extending between the ears and 130

being engageable with one of the aforesaid shoulders, a fulcrum block arranged between the free ends of said ears and slidably engaging the lower edge of said bar, being also adapted to engage the remaining shoulder to limit the movement of the arm in one direction, a spring-pressed dog pivoted between the inner ends of the ears and extending beyond the adjacent end of

said arm, being engageable with the teeth of said rack bar, a hand-actuated operating lever pivoted on said bar and including means engageable with the teeth on said arm for imparting a sliding movement to the latter.

In testimony whereof I have hereunto set my hand.

ANSLEY BARNES.
